UNITED STATES PATENT OFFICE.

JAMES C. WOODSON, OF MANSFIELD, OHIO, ASSIGNOR TO WESTINGHOUSE ELECTRIC & MANUFACTURING COMPANY, A CORPORATION OF PENNSYLVANIA.

TUBULAR HEATER AND METHOD OF MAKING THE SAME.

Application filed September 2, 1926. Serial No. 133,187.

My invention relates to tubular heaters, and particularly to flattened tubular heaters and a method of making the same. 50

An object of my invention is to provide a simple and efficient tubular heater.

Another object of my invention is to provide a method of making flattened tubular heaters.

A further object of my invention is to 10 provide means in a flattened tubular heater to prevent short-circuiting of the heating coil.

Other objects of my invention will be apparent from the disclosure.

15 It has been found that in making a flattened tubular heater, and particularly where the heating coil is insulated by means of initially metallic, expansively oxidizable material, there is danger of the two sides of a 20 flattened coil coming into contact with each other and thereby causing a short-circuit. By my invention I am able to obviate this difficulty.

In practicing my invention, according to 25 the present embodiment, a heating coil has inserted within it an initially metallic expansively oxidizable material and such material may also be placed on the outside of the coil. These parts are then placed within 30 a pipe that may be cylindrical and the oxidizable material oxidized by suitable means, such as steam under pressure. The method employed is more particularly disclosed and claimed in Reissue Pat. No.

35 16340 to C. B. Backer. The oxidized material expands to about 200% of its original volume thereby filling all of the available space. The pipe and coil are then flattened and the expansively oxidized material within 40 in the coil will prevent short-circuiting between opposite sides of a flattened coil.

In the drawing, Fig. 1 is a longitudinal view, partially in section, of a pipe with a heating coil therein before oxidation of the 45 initially-metallic material;

Fig. 2 is a transverse sectional view there- through, taken on the line II—II of Fig. 1;

Fig. 3 is a longitudinal view, partially in

section, similar to Fig. 1, but showing the completed tubular heater; and

Fig. 4 is a transverse sectional view taken on the line IV—IV of Fig. 3.

Referring to the drawing for a more complete description of the present embodiment of my invention, an electric heating coil 10 55 is placed in a coil 12 of initially metallic, expansively oxidizable material. A coil 14 composed of the same material as the coil 12, but of smaller diameter, is placed within the coil 10, as is shown in Figs. 1 and 2. The 60 assembled coils may then be placed in the pipe or tube 16 that may be metallic.

After the coils 10, 12 and 14 are placed in the pipe 16, the entire assembly is placed in a suitable compartment, such as an autoclave, and subjected to the action of an oxidizing agent, such as steam under pressure. After having been treated for the proper length of time, the coils 12 and 14 will be 65 oxidized and, as a result, the coil 10 will be imbedded in refractory insulating material. If the coils 12 and 14 are made of magnesium, the resulting oxidized material will be 70 magnesium oxide.

The pipe 16 and the coil 10 are then flattened by any suitable means, such as a rolling machine. After thus being flattened, the tubular heater will have the general appearance shown in Figs. 3 and 4. If the ends of the coil 10 are connected to a source 75 of electrical energy, the device will operate 80 as a heater.

By placing the coil 14 within the coil 10, opposite sides 18 and 20 of the flattened coil will be prevented from coming in contact 85 with each other during the process of flattening, since there will be a layer of initially-metallic expansively-oxidized insulating material therebetween. Any danger of short-circuiting will, therefore, be obviated. 90

While the initial shape of the pipe 16 and the coils 10, 12 and 14 is shown as cylindrical, it is obvious that other shaped coils and pipes might be utilized.

While I have shown and described for 95 purposes of illustration a particular form of

my invention, it may, of course, be embodied in other forms without departing from the spirit and scope thereof, as set forth in the appended claim.

5 I claim as my invention:

The method of making a tubular heater that comprises placing coils of initially metallic expansively oxidizable material both

within and without a heating coil of substantially cylindrical shape, placing the coils in a cylindrical tube, oxidizing the material and flattening the tube and the material therein.

In testimony whereof, I have hereunto subscribed my name this 18 day of Aug. 1926.

JAMES C. WOODSON.
